UNITED STATES PATENT OFFICE.

MILLER REESE HUTCHISON, OF SUMMIT, NEW JERSEY.

DIAPHRAGM-HORN.

1,052,416.

Specification of Letters Patent. Patented Feb. 4, 1913.

Application filed October 26, 1909. Serial No. 524,761.

To all whom it may concern:

Be it known that I, MILLER REESE HUTCHISON, a citizen of the United States, and a resident of Summit, in the county of 5 Union and State of New Jersey, have invented certain new and useful Improvements in Diaphragm-Horns, of which the following is a specification.

My present invention relates to horns or 10 signaling devices wherein a vibratory member such as a diaphragm is actuated by power derived from a rotary member or drive shaft, which may be the armature shaft of an electric motor.

15 In my prior Patents Nos. 923,048, 923,049, and 923,122 I have disclosed various means through which movement of a rotary member may be applied to operate the diaphragm, as, for instance, a tension member, 20 a thrust member, or a combined tension and thrust member, any of which may be either rigidly or pivotally mounted upon the diaphragm and may be tightly coupled to the driving means, or may be loosely 25 coupled so that only a part of the movement of the diaphragm is forced by the driving means, the diaphragm being permitted any desired degree of independent motion in either or both directions. The motion im-

30 parted to the diaphragm through such devices has been derived through cams, cranks, or other thrust surfaces eccentrically arranged upon a member rotating about an axis approximately parallel to the 35 diaphragm. As stated in said patents, the specific mechanisms shown and described therein are merely illustrative of a great variety of forms covered by but not specifically described in said patents, and my 40 present invention includes novel driving means especially adapted for similar uses, but which may be employed in other relations where their functions or advantages may prove useful.

45 More specifically considered, my present invention involves an arrangement of parts whereby the vibratory motions of the diaphragm may be derived from a drive shaft, such as the armature shaft of an electric 50 motor, when such shaft is arranged at an angle to the plane of the diaphragm instead of parallel therewith. This is particularly desirable in the cases where the armature shaft of an electric motor is utilized as the drive shaft, since it permits a 55 compact arrangement of the motor within a case which need not extend peripherally

outside of the circumference required for inclosing the diaphragm. In certain cases the armature shaft may be perpendicular 60 to the diaphragm, and if desired, may be arranged concentrically therewith so that its axis passes through the center of the diaphragm. With the latter arrangement the motor case may be perfectly symmet- 65 rical.

My invention includes means whereby the rotary motion about an axis non-parallel with the diaphragm may be applied for vibrating the latter, as, for instance, face 70 cams, or face projections carried by the rotary member, and also a great variety of mechanical movements adapted to transform rotary motion into reciprocating motion in a direction approximately parallel 75 to the axis of the rotary motion.

Having thus described the nature of my invention, I will now describe certain practical embodiments thereof in connection with the accompanying drawings which 80 show a vertical longitudinal section of the device.

In the drawings are shown the horn or resonator 1, front case 2, peripheral flange 3, diaphragm 4, clamps 5 and 6, and cork-like gaskets 7 and 8 which may be of any known construction and are in fact similar to one of the forms shown in my prior application, Ser. No. 494,120, filed May 5, 1909. The wear piece 9, secured to the center of the diaphragm, may be of any known or approved construction, but is preferably a flat steel plate brazed, welded or otherwise secured thereon.

The drive shaft 10 is the shaft of armature 95 13 energized through brushes 14 and commutator 15, rotating within the field of pole pieces 16 and 17, energized by coils 18, 19. The motor may be any suitable rotary motor, though for most purposes I prefer 100 a low voltage direct current, shunt-wound motor adapted to rotate always in one direction, regardless of the polarity of the current supplied thereto.

While the cam described in my applica- 105 tion of even date herewith is an efficient means for transforming the rotary motion of the drive shaft into vibratory motion of a diaphragm at an angle thereto, by partly forced and partly free movements, I may 110 employ any other desired mechanical movement for this purpose, preferably such as will permit arranging the drive shaft with its axis passing through the center of the

diaphragm, preferably perpendicular thereto. In the arrangement shown, the motor being symmetrically arranged with respect to the center of the diaphragm, the inclosing case is concentric therewith, and the entire device is symmetrical with respect to a straight line passing through the axis of the horn and the center of the diaphragm.

- 10 The means for applying the rotary motion of the armature shaft to the diaphragm consists of a member connected thereto in such manner as to be rotated through and at the same time to be free for movement parallel with the axis thereof. The rotary movement of such member is utilized to produce its longitudinal movement by cam engagement with a suitably supported relatively fixed member.
- 20 By reference to the drawings it will be seen that the face cam 33 is a member mounted for rotary movement with the armature shaft and is free for movement parallel with the axis by reason of the spline 32. The stationary abutment or cam projection 34 is the means for causing the rotary movement of the cam to produce the longitudinal movement. The abutment 34 is carried by adjustable screw 35 carrying 30 an adjustable thumb-nut 36. In the form shown in the drawing a spring 37 is interposed between the head of the projection 34 and the wall of the case so as to maintain the projection in a position as far forward as the adjustment of the nut 36 will permit. Obviously the functions would be the same if the rotary member 33 had only one projection and the stationary member was a circular face cam. The reciprocating right line motion attainable by the above is utilized to vibrate the diaphragm. In the form shown in the drawings this is effected through the medium of a member 30 extending entirely through the armature shaft and provided adjacent the diaphragm with a suitable diaphragm engaging portion 40. A hardened wear piece or anvil 9 may be interposed between the diaphragm and the member 40 if desired. This arrangement 40 has the advantage that the power is applied to the diaphragm at the center and perpendicular thereto so that there is no lateral component of the thrust and there can be no reverse bending effect upon the diaphragm. It results that the motion of the latter is a bodily movement adapted to produce a definite acoustic wave of great intensity.
- 50 While I have herein fully shown and described, and have pointed out in the appended claims certain novel features of construction, arrangement, and operation which characterize my invention, it will be understood by those skilled in the art that various omissions, substitutions, and changes in

the forms, proportions, sizes, and details of the device and of its operation, may be made without departing from my invention.

I claim:

1. In a horn or signaling device, a diaphragm in combination with a rotary shaft and means for applying the power of said shaft to agitate said diaphragm, said means including a member rotated by said shaft but free for longitudinal movement with respect thereto, and coöperating means whereby the rotary movement of said last mentioned member causes the longitudinal movement thereof, the location and relative arrangement of the parts being such that said longitudinal movement serves to agitate the diaphragm. 70

2. In a horn or signaling device, a diaphragm in combination with a rotary shaft and means for applying the power of said shaft to agitate said diaphragm, said means including a member rotated by said shaft but free for longitudinal movement with respect thereto, and means for causing such longitudinal movement and utilizing the latter to agitate the diaphragm. 80

3. In a horn or signaling device, a diaphragm in combination with a rotary shaft and means for applying the power of said shaft to agitate said diaphragm, said means including a member rotated by said shaft but free for longitudinal movement with respect thereto, coöperating means whereby the rotary movement of said last mentioned member causes the longitudinal movement thereof, the location and relative arrangement of the parts being such that said longitudinal movement serves to agitate the diaphragm and said member and coöperating means being relatively adjustable in a direction longitudinal of said shaft. 100

4. In a horn or signaling device, a diaphragm in combination with a rotary shaft and means for applying the power of said shaft to agitate said diaphragm, said means including a member rotated by said shaft but free for longitudinal movement with respect thereto, coöperating means whereby the rotary movement of said last mentioned member causes the longitudinal movement thereof, said longitudinal movement being utilized to agitate the diaphragm. 110

5. In a horn or signaling device, a diaphragm, in combination with a rotary driver arranged with its axis approximately normal to said diaphragm, and means for applying the power of said rotary driver to agitate said diaphragm, said means including a member rotatably driven by said driver and arranged for to and fro movement with respect to the diaphragm, and coöperating relatively stationary means whereby the first mentioned movement imparted to said member by the driver causes the said movement with respect to the diaphragm. 120

130

6. In a horn or signaling device, a diaphragm, in combination with a rotary driver arranged with its axis approximately normal to said diaphragm, and means for applying the power of said rotary driver to agitate said diaphragm, said means including a member rotatably driven by said driver and arranged for to and fro movement with respect to the diaphragm, and coöperating means including an inclined surface whereby the first mentioned movement imparted to said member by the driver causes the said movement with respect to the diaphragm.

15 7. In a horn or signaling device, a diaphragm, in combination with a rotary motor arranged with its armature shaft approximately normal to said diaphragm, at its center and means for applying the power of said shaft to agitate said diaphragm, said means including a member rotatable with said shaft and arranged for to and fro movement with respect to the diaphragm, and coöperating relatively stationary means whereby the first mentioned movement imparted to said member, causes the said movement with respect to the diaphragm.

20 8. In a horn or signaling device, a diaphragm, in combination with a rotary motor arranged with its armature shaft approximately normal to said diaphragm, and means for applying the power of said shaft to agitate said diaphragm, said means including a member rotated by said shaft and arranged for to and fro movement with respect to the diaphragm, and coöperating means including an inclined surface whereby the first mentioned movement imparted to said member causes the said movement

25 with respect to the diaphragm.

30 9. In a horn or signaling device, a diaphragm, in combination with a rotary motor arranged with its armature shaft at an angle to said diaphragm, and means for applying the power of said shaft to agitate said diaphragm, said means including a member rotatably driven by said shaft and arranged for movement toward and away from the diaphragm and coöperating means including a stationary cam whereby the circular movement of said member causes it to move toward the diaphragm, the construction and relative arrangement being such that the reaction from the diaphragm is in

35 the direction of the return movement of said member.

40 10. In a horn or signaling device, a diaphragm, in combination with a rotary driver arranged with its axis approximately normal to said diaphragm, and means for applying the power of said driver to agitate said diaphragm, said means including a

45 member rotatably driven by said driving member and arranged for movement toward and away from the diaphragm, and coöperating means including an inclined surface whereby the circular movement of said member causes it to move toward the diaphragm, the construction and relative arrangement being such that the reaction from the diaphragm is in the direction of the return movement of said member.

50 11. In a horn or signaling device, a diaphragm, in combination with a rotary electric motor arranged with its armature shaft approximately normal to said diaphragm at its center, and means for applying the power of said shaft to agitate said diaphragm, said means including a member rotatably driven by said shaft and arranged for movement toward and away from the diaphragm, and coöperating means including an inclined surface whereby the circular movement of said member causes it to move toward the diaphragm, the construction and relative arrangement being such that reaction from the diaphragm is in the direction of the return movement of said member.

55 12. In a horn or signaling device, a diaphragm in combination with a rotary electric motor arranged with its armature shaft at an angle to the diaphragm, and means for applying the power of said shaft to agitate said diaphragm, said means including a thrust member carried by and secured for rotation with said shaft but free for longitudinal movement with respect thereto, coöperating means whereby the rotary movement of said shaft member causes longitudinal movement of said thrust member, the location and relative arrangement of the parts being such that said longitudinal movement serves to agitate the diaphragm.

60 13. In a horn or signaling device, a diaphragm in combination with a rotary shaft and means for applying the power of said shaft to agitate said diaphragm, said means including a thrust member carried by said shaft but free for longitudinal movement with respect thereto, coöperating means whereby the rotary movement of said shaft member causes the longitudinal movement of said thrust member, the location and relative arrangement of the parts being such that said longitudinal movement serves to agitate the diaphragm.
